UNITED STATES PATENT OFFICE.

ROBERT CARLSON, OF GREENWICH, CONNECTICUT.

GAME.

Application filed September 19, 1923. Serial No. 663,528.

To all whom it may concern:

Be it known that I, ROBERT CARLSON, a citizen of the United States, and a resident of the city of Greenwich, in the county of 5 Fairfield and State of Connecticut, have invented certain new and useful Improvements in Games, of which the following is a specification.

My invention relates to an improvement 10 in games, and one of the objects thereof is to provide a game which is inexpensive and simple to manufacture, and yet amusing and interesting to the players, the construction of the various devices employed being of 15 such a nature that considerable skill is required in playing the game.

In general my improved game comprises 20 a wheel, provided with wings or paddles, which is spun by driving a ball against the paddles, the wheel being provided or co-operating with an indicator designating the 25 next play to be made. In addition stakes are provided which may be driven into the ground some distance from the wheel, the object being to encircle each of the stakes and finally return to the starting point, the order in which the stakes are passed or encircled depending upon the spinning of the wheel.

30 In the accompanying drawings I have made provision for six (6) players, but this number may be varied, of course, as desired. The balls employed in playing the game are driven with a mallet, each mallet and its 35 ball being correspondingly colored so that each player may always be certain of his ball, while one of the stakes—preferably the starting stake—is provided with colored stripes or other indicia indicating the order 40 in which the players are to play. The paddles of the wheel are also colored to correspond to each mallet and its ball, and each player is required to strike his own paddle or wing.

45 In the accompanying drawings—

Figure 1 shows in elevation the improved wheel employed in the game;

Fig. 2 is a plan view of the wheel of Fig. 1, and

50 Fig. 3 is a more or less diagrammatic view of the entire apparatus showing the stakes and wheel, etc., in position.

Referring to the drawings in detail, 1 designates the base or bottom portion of my improved wheel, this base being provided with

a stake 2 adapted to be driven into the ground when the game is played out of doors. If the game is to be played indoors, the lower part of the stake is omitted.

The indicator 3, which is used for indicating the plays to be made, is a thin plate made of sheet metal, for example, or other suitable material and divided on the face thereof into six (6) sections, 4, 5, 6, 7, 8 and 9, respectively, as indicated in Fig. 2. It 60 will be understood that the number of sections into which the indicator is provided may be varied, as desired. The indicator has a central aperture 10 and eccentric apertures 11 and 12, respectively, and is held in 65 place upon the member 1 by means of a washer or locking member 13 provided with pins 14, which pass through the holes 11 and 12 in the indicator and are received by apertures or holes in the base member 1. This 70 arrangement effectively holds the indicator in place on the base of the wheel. The rotor of the wheel comprises a hub 15—preferably, though not necessarily, made in two (2) pieces—which is slipped over the top of 75 the stake 2 already referred to, the wheel, when the game is being played, being spun about this stake. Clamped between the upper and lower members constituting the hub or rotor 15 are paddles 16, 17, 18, 19, 20 and 80 85 21, the lower edge of each paddle falling short of the base of the support 1, to enable the wheel to be spun or rotated with the base 1 resting upon the ground.

The paddles or wings 16, 17, 18, etc., are 90 colored to correspond to the mallets 22 and balls 23. For example, the paddle or wing 16 has been illustrated as red in color, its corresponding mallet 22 and ball 23 being 95 likewise colored red—which indicates that the red ball must be driven by the red mallet against the red paddle.

The pegs, of which there are five (5), are designated 24, while 25 designates a starting and home stake. This stake is striped or 100 otherwise colored, as indicated at 26, to correspond to the colors used on the paddles and mallets, etc. This coloring on the starting stake is to indicate the order of play. In other words, if the colors in the starting 105 stake run red, green, blue, etc., the balls are played red, green, blue, etc.

In use the wheel is assembled as shown in Figs. 1 and 3, and held in position on the ground by the stake 2. The pegs 24 and 110

stake 25 are then disposed about the wheel at equal distances apart and as far from the wheel as may be desired.

The first to play is the player holding the 5 mallet and ball corresponding to the first or last colored stripe on the stake 25. Starting from the home stake, this player drives his ball against the paddle bearing his color. Assuming the paddle is hit, the wheel is 10 spun and a reading taken from the indicator 3, which will indicate the play to be made the next time this player's turn to play is reached. The object of the game is to encircle each of the pegs 24, the player 15 being required to drive to the wheel each time after encircling a peg. The player first encircling all of the pegs and striking the home or starting stake is the winner.

While I have described a specific manner 20 of playing my improved game, it is to be understood that this may be departed from within the purview of my invention.

What I claim is:

1. In a game apparatus, the combination 25 of a wheel provided with wings or paddles, a support for the wheel and on which the wheel is adapted to be rotated, and an indicator fixed relatively to said support and provided with playing instructions, said paddles or wings being movable over the 30 face of said stationary indicator, whereby as the wheel is rotated the next play to be made will be indicated.

2. In a game apparatus, the combination 35 of a rotatable wheel provided with a plurality of wings or paddles, an indicator located below said wheel co-operating with said paddles or wings, each of said paddles or wings being of a different color from the 40 others, and balls colored to correspond with each paddle and adapted when driven to strike the correspondingly colored paddle to rotate the wheel, the indicator co-operating with said paddles when the wheel is rotated 45 to indicate the next play to be made by the ball which rotated the wheel.

3. In a game apparatus, the combination

of a wheel provided with a plurality of wings or paddles each bearing a different color, a support for the wheel, an indicator 50 independent of said wheel and having indicia thereon, said indicator being secured to said support and held against rotation relatively thereto, a plurality of balls, each ball being colored to correspond to one of the wings or paddles of said wheel, and mallets each of which is colored to correspond to a correspondingly colored ball, said mallets and balls co-operating with said wheel to rotate the same, said indicator co-operating with the wings or paddles of said wheel to indicate the next play to be made. 55

4. In a game apparatus, the combination 60 of a wheel provided with a plurality of wings or paddles of different colors, an indicator co-operating with said paddles or wings, a plurality of pegs spaced from said wheel and equally spaced from each other, a home stake in line with said pegs, a plurality of balls, each ball being colored to 65 correspond to one of the paddles or wings of said wheel, and a plurality of mallets each colored to correspond to its respective ball, said wheel being rotated by driving a ball of a certain color against a wing or 70 paddle of the same color, said indicator co-operating with said wheel to indicate the next play to be made by said last mentioned ball in causing the ball to advance from the home stake to said wheel and from thence 75 around each of said pegs.

5. In a game apparatus, the combination 80 of a support, an indicator carried thereby and frictionally held against rotation relatively to said support, a wheel having a hub superimposed on said indicator, paddles carried by said hub and movable over the face 85 of said indicator, and a pin or stake adapted to pass through said hub indicator and support to hold said members in operative relative positions.

This specification signed this 14th day of September, 1923.

ROBERT CARLSON.
